COMBINED ARTIFICIAL EYELASHES AND DISPLAY BOX

David H. Aylott, 58-60 Bridge Road E.,
Welwyn Garden City, England

Filed Jan. 26, 1968, Ser. No. 10,331

Claims priority, application Great Britain Dec. 12, 1967

Term of patent 7 years

Int. Cl. D9—04; D28—02

U.S. Cl. D9—187

FIG.1.

FIG.2.

FIG.3.

FIG.4.

FIG. 1 is a top plan view of the combined artificial eyelashes and display box showing my new design in an open condition;

FIG. 2 is a front elevation thereof of FIG. 1;

FIG. 3 is an end elevation thereof as seen from the left of FIG. 2;

FIG. 4 is a section thereof taken on lines 4—4 of FIG. 2, and

FIG. 5 is a top perspective view thereof.

The top, bottom and sides of the container are of flat planar configuration.

I claim:

The ornamental design for combined artificial eyelashes and display box, as shown and described.
